CLAIM

The ornamental design for a cam for a compound bow, as shown and described.

DESCRIPTION

FIG. 1 is a perspective view of the cam for a compound bow; showing my new design;

FIG. 2 is a left side elevation of the cam for a compound bow;

FIG. 3 is a right side elevation thereof;

FIG. 4 is a rear elevation thereof;

FIG. 5 is a front elevation thereof;

FIG. 6 is a top elevation thereof; and,

FIG. 7 is a bottom elevation of the cam for a compound bow illustrated in FIGS. 1-6.
